UNITED STATES PATENT OFFICE.

MELVILLE D. JONES, OF SOMERVILLE, MASSACHUSETTS.

DESIGN FOR A GRAVE-MARKER.

SPECIFICATION forming part of Design No. 24,059, dated February 19, 1855.

Application filed April 5, 1894. Serial No. 506,510. Term of patent 7 years.

To all whom it may concern:

Be it known that I, MELVILLE D. JONES, a citizen of the United States, residing at Somerville, county of Middlesex, State of Massachusetts, have invented and produced a new and original Design for a Grave-Marker, of which the following is a specification, reference being had to the accompanying drawings, showing a representation thereof.

10 Figure 1 is a front elevation of a grave-marker showing my design. Fig. 2 is an edge view, and Fig. 3 is a top view, these three views being deemed necessary to fully illustrate my design.

15 My design includes a circular tablet on which is the figure of a minute man with stars about him, together with a cross. In this design the tablet appears as the centerpiece of the cross, while a wreath of laurel hangs behind the cross.

In the illustration of this design 2 represents a straight shaft surmounted with a cross which comprises four arms 3, 4, 5, 6, having a stippled or roughened surface, and with re-enter-

ing angles at the ends of the arms, whereby 25 two points are created on each arm. These points of the cross are capped with balls or spheres 7. At the meeting point of the arms of the cross is placed a centerpiece in the shape of a circular tablet 8. Upon this tablet 30 is shown the figure of a minute man surrounded by thirteen stars.

In the rear of the cross appears a wreath composed of myrtle leaves 9 in conventional form; while the ends of the wreath are tied 35 in a knot at a point below the cross.

Projecting rearwardly from the marker behind the cross are shown two short bosses 12.

What I claim is—

The design for a grave-marker, substantially as herein shown and described.

In testimony whereof I have affixed my signature in presence of two witnesses.

MELVILLE D. JONES.
